(57) **CLAIM**

The ornamental design for a susceptor assembly, as shown and described.

DESCRIPTION

FIG. 1 is a top perspective view of a susceptor assembly showing our new design;

FIG. 2 is a bottom perspective view thereof;

FIG. 3 is a top plan view thereof;

FIG. 4 is a bottom plan view thereof;

FIG. 5 is a front view thereof, the back view being a mirror image thereof; and,

FIG. 6 is a side view thereof, the opposite side view being a mirror image thereof.

The broken lines in the figures form no part of the claimed design.
